BOAT CANOPY AND FRAME

William R. Reynolds, Dallas, Tex.

Application August 4, 1947, Serial No. 765,875

4 Claims. (Cl. 135—6)

1

This invention relates to foldable canopy frames and more particularly to collapsible canopy frames for boats.

The principal object of the invention is to provide a canopy frame consisting of a pair of spaced apart bows of resilient material, each comprised of pivoted sections, the free ends of which carry clamps for securing to the sides of a boat. Moreover, the invention includes a flexible canopy whose width is equal to half the length of a bow and whose ends carry rings embracing the bows to enable the canopy to be moved on the latter with the diurnal travel of the sun to shield the occupants of the boat against the rays thereof.

Another object of the invention is to provide a canopy frame for boats which, by virtue of its foldability, can be readily carried, stored or shipped in a comparatively small space and because of its simple construction, the frame is easy to install and as easily detached from a boat.

With the foregoing objects in view, the invention has further reference to certain features of accomplishment which will become apparent as the description proceeds, taken in connection with the accompanying drawing wherein:

Figure 1 is a fragmentary perspective view of a boat showing the invention mounted thereon.

Figure 2 is a fragmentary view of one of the bows showing the manner in which the canopy is attached thereto.

Figure 3 is a fragmentary view of the bow hinge in longitudinal section, showing a collar serving as the means for securing the canopy in adjusted positions on the bows, and

Figure 4 is a fragmentary perspective view of one of the bows and canopy, showing the manner in which the bows are folded.

Continuing with a more detailed description of the drawing, reference is primarily made to Figure 1 wherein numeral 10 denotes a boat, to the side rails 11 of which is secured the ends of a pair of bows in spaced apart relationship and generally indicated by reference numeral 12.

Each of the bows 12 consists of end sections 13 and an intermediate short section 14, to which the inner ends of the end sections are pivoted at a. The pivots a are spaced inwardly from the ends of the intermediate section 14 and adjacent the ends thereof are dimples 15 (Figure 3) which correspond with similar dimples 16 in the end sections 13 to hold the sections in longitudinally aligned relationship preparatory to forming the arc shown in Figure 1.

The material of the bows is of a resilient

2

characteristic in order that when tension thereon is relieved, the bow sections will resume a straight position and the sections 13 and 14 may be folded into relative parallelism.

On the end of each end section 13 is mounted a substantially U-shaped member 16 serving as a clamp by which the bow is secured to the sides 11 of the boat 10. A bolt 17 passes through one leg of the member 16 and bears against the boat 10 rail to secure the clamp thereon.

A canopy 18 of fabric or the like is adjustably mounted on the bows 12. The width of the canopy is equal to approximately half the length of a bow in order that it will shield from the sun's rays only the occupied portion of the boat exposed thereto, leaving adequate opening for ventilation.

In each end of the canopy 18 is a seam 19 enclosing a cord 20. Notches 21 are made in the edge of the canopy to expose the cord. Rings 22 embrace the exposed cord and likewise encircle the bows 12 in the manner shown and are slideable thereon so that the canopy may be adjusted to follow the diurnal travel of the sun.

As a means to secure the canopy in adjusted positions, a collar 23 is mounted on each end of a resilient strip 24, passed through a seam 25 along each side edge of the canopy. A wing bolt 26 on the collar 23 holds the same against dis- placement from adjusted positions on the bow.

Manifestly, the construction as shown and described is capable of some modification and such modification as may be construed to fall within the scope and meaning of the appended claims is also considered to be within the spirit and intent of the invention.

What is claimed is:

1. A boat canopy including a frame comprised of a pair of spaced apart bows, each consisting of a pair of end sections and an intermediate section of resilient material, between the ends of which latter section the ends of said end sections are pivoted, means jointly carried by said sections for retaining the same in longitudinally aligned relationship, a canopy whose width is substantially less than the length of said bows and extending between the same, rings spaced along each end of said canopy and embracing said bows for adjustability thereon and means at each corner of said canopy for securing the latter in adjusted positions on said bows.

2. A boat canopy including a pair of resilient bows comprised of a pair of end sections and a short intermediate section, to which the end sections are pivoted adjacent their inner ends, means

carried jointly by said end and intermediate sections for retaining the same in longitudinally aligned relationship, means on the outer end of the end section of each bow for securing said bows to the sides of a boat, a canopy whose width is substantially half the effective length of said bow sections in extended position, rings spaced along each end of said canopy embracing said bows for adjustability of said canopy thereon and means at each corner of said canopy for securing the same in adjusted positions on said bows.

3. In a boat canopy, a foldable frame comprising bows, each consisting of longitudinally alignable end sections of resilient material and a short intermediate section to which said end sections are pivoted, a canopy having rings on each end thereof loosely embracing said bows, a stiffening strip passing through a hem in each side edge of said canopy, means on each end of each strip for securing said canopy against displacement from adjusted positions on said bows and means carried jointly by the end and intermediate sections of said bows to hold the same in extended position.

4. In a boat canopy, a pair of frame members, each consisting of a plurality of outer and inner

flat resilient strips pivoted together in end to end relationship and adapted to be sprung into arcuate form to constitute a bow, said strips jointly carrying means by which they are held in extended relationship but are capable of being folded to dispose the outer of the strips in relative parallelism and at substantial right angles with the inner strip, a canopy having a series of spaced apart rings in each end adapted to loosely embrace said bows and means carried by said canopy to hold the same in adjusted positions on said bows.
